US00D831925S

(12) **United States Design Patent** (10) **Patent No.:** **US D831,925 S**
(45) **Date of Patent:** **** Oct. 30, 2018**

(54) **CONFECTIONERY BAR SEGMENT**

(71) Applicant: **MARS, INCORPORATED**, McLean, VA (US)

(72) Inventors: **Carsten Astheimer**, Ambleside (DE); **Timothy Moore**, Gillygooley (GB); **Robert Benjamin Foskett**, Telford (GB); **Sam Tarratt**, Slough (GB)

(73) Assignee: **Mars, Incorporated**, Mclean, VA (US)

(**) Term: **15 Years**

(21) Appl. No.: **29/635,832**

(22) Filed: **Feb. 2, 2018**

Related U.S. Application Data

(62) Division of application No. 29/524,981, filed on Apr. 24, 2015, now Pat. No. Des. 809,240.
